DESIGN FOR A NEGLIGEE

Violet Giovagnoni, New York, N. Y.

Application February 9, 1942, Serial No. 105,717

Term of patent 3½ years

To all whom it may concern:

Be it known that I, Violet Giovagnoni, a citizen of the United States, residing in New York city, in the county of New York and State of New York, have invented a new, original, and ornamental Design for a Negligeé, of which the following is a specification, reference being had to the accompanying drawing, forming part thereof.

Fig. 1 is a front view of a negligeé showing my design.

Fig. 2 is a rear view of the negligeé shown in Fig. 1 on a reduced scale, and

Fig. 3 is an enlarged fragmentary view of the negligeé shown in Fig. 1, with the belt portion turned back.

I claim:

The ornamental design for a negligeé, substantially as shown.

VIOLET GIOVAGNONI.
